UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

HAND BRAKE.

Application filed December 14, 1922. Serial No. 606,926.

This invention relates to improvements in hand brakes.

An object of my invention is to provide, in a hand brake for railway and other cars, means for quickly taking up the slack in the brake chain and automatically increasing the leverage ratio pull on the brake chain during the final application of the braking pressure. A further object of my invention is to provide, in a device of this type, automatically operable means for adjusting the brake mechanism to compensate for excessive slack in the brake chain.

A more specific object of the invention is to provide a hand brake of the vertical staff type with chain-winding means comprising a pair of normally simultaneously rotated drums having different peripheral winding speeds and each drum receiving one end of the chain wound thereon and means automatically operated upon the slack having been taken up for stopping the operation of the winding drum having the greater peripheral speed while continuing the operation of the other winding drum, thereby increasing the effective leverage ratio pull on the brake chain, together with means for automatically compensating for all increase in the slack of the brake chain due to wear of the brake shoe faces and other parts of the brake rigging, thus keeping substantially constant the number of turns of the brake staff to apply the brakes.

Other objects of the invention will more clearly appear from the description and claims hereinafter following.

In the drawing forming a part of this specification, Figure 1 is a side elevation of a hand brake showing my improvements in connection therewith. Fig. 2 is a horizontal sectional view taken substantially on the line 2—2 of Fig. 1. Fig. 3 is a bottom plan view of a clutch cap used in my improved hand brake. Fig. 4 is a horizontal sectional view taken substantially on the line 4—4 of Fig. 1. And Fig. 5 is a horizontal sectional view taken substantially on the line 5—5 of Fig. 1.

In said drawing, 10 denotes the end wall of a car, to which is attached by any suitable means such as rivets 11 the horizontal angle beam 12 forming the top of the built up end sill indicated generally by A. The channel beam 13 forming the side wall of the end sill A is suitably secured to the outer

edge of the beam 12, by means of rivets 14 or any other suitable means passing through the angularly projecting flange 15 of the beam 13 and the end of the bracket 12. A stirrup 16 comprising a horizontally extending bottom plate 17 and vertically extending side walls 18 is suitably attached to the bottom of the end sill A. A horizontal plate 19 arranged between the walls 18 is attached to the inwardly projecting flange 20 at the lower edge of the plate 18 by any suitable means such as rivets 21.

A vertically extending brake staff 22 is shown, the same having a hand wheel 23 rigidly secured to its upper end and a relatively small gear 24 fixed to its lower end to rotate in unison therewith. The lower end of the brake staff 22 extends outwardly beyond the gear 24 and is reduced as shown at 25, said reduced portion 25 being journaled in an opening 26 in the plate 17 of the stirrup. The staff 22 has loosely rotatably mounted thereon, a sleeve 27, the latter passing through the beam 12 and plate 19, and journaled in openings 28 and 29 in the beam 12 and plate 19, respectively.

A chain-winding drum 30 is rotatably mounted between the plate 19 and bottom plate 17 of the stirrup having its upper end journaled in an opening 31 in the plate 19 and its lower reduced end 32 journaled in an opening 33 in the bottom plate 17. Fixed to the drum 30 is a relatively large gear 34 meshing with the gear 24 on the staff 22 whereby rotation of the staff in the direction of the arrows as indicated in Fig. 5 will cause rotation of the gear 34 and the drum 30 in a direction reversely thereto as indicated by the arrow associated with these latter parts, as shown in Fig. 5.

The staff 22 is formed with a squared portion 35 adapted to slidably but non-rotatably receive the collar 36. The latter is provided with ratchet teeth 37 on its periphery and clutch teeth 38 on its lower face, said clutch teeth 38 coacting with clutch teeth 39 formed on the enlarged upper end 40 of the sleeve 27. The periphery of the enlarged end 40 is provided with ratchet teeth 41 corresponding with the ratchet teeth 37 of the sliding collar 36.

Accidental rotation of the collar 36 and the sleeve 27 in a counter-clockwise or chain unwinding direction is prevented by the pivoted locking pawls 42 and 43 which

co-act respectively with the teeth 37 on the collar 36 and the teeth 41 on the sleeve 27. The pawls 42 and 43 are suitably pivoted on the bracket 12 by a bolt 44 and are provided with operating levers 45 and 46 respectively, for disengaging the same from the respective ratchet teeth 37 and 41. The pivoted pawl 42 is so mounted that it may have independent movement relative to the pawl 43 so that the pawl 43 may remain in engagement with the ratchet teeth 41 to prevent retrograde movement of the sleeve 27 while the pawl 42 has a ratcheting action over the teeth 37 of the collar 36.

15 The sleeve 27, as shown in Fig. 1, has its lower end extending beyond the plate 19 and rests upon the gear 24, thus providing a chain winding drum portion 47. The chain winding drum portion 47 is provided 20 with a laterally projecting lug 48 adapted to serve as an anchorage for the brake chain. The teeth 39 on the enlargement 40 of the sleeve 27 which co-act with the teeth 38 on the collar 36 are so designed that their 25 inclination will offer sufficient resistance to prevent slippage of the parts during the time that the slack in the brake chain is being taken up. The resistance between the teeth 38 and 39 is insufficient, however, to 30 prevent slippage after a predetermined resistance is encountered in the tightening of the chain.

35 Rotatably journaled and slidably mounted upon the sleeve 27 is a hollow stop cap 49 provided with inwardly projecting oppositely located lugs 50, adapted to co-act with oppositely located outwardly projecting lugs 51 on the sleeve 27. The lower edge of the 40 stop cap 49 is provided with a series of ratchet teeth 52, co-acting with an annular set of ratchet teeth 53, formed integral with the plate 19. The ratchet teeth 52 and 53 are so arranged that the stop cap 49 is 45 adapted to rotate in a clockwise direction, but is positively prevented from rotation in a counter-clockwise direction.

50 The brake chain 54 has one end secured to the anchorage 48 on the winding drum 47 and extends over a grooved pulley 55 journaled in the end of the brake rod 56 and has its opposite end secured to the brake drum 30 by means of an anchoring bolt 57.

55 In the operation of my improved brake mechanism, the hand wheel 23 is turned in a clockwise direction to tighten the brakes. During the normal operation of the device, upon rotation of the hand wheel in said clockwise direction, the chain winding drums 30 and 47 will be simultaneously rotated but in opposite directions, as indicated by the arrows in Fig. 5, thus winding the opposite ends of the chain 54 thereon and effecting a very rapid movement of the end of the brake rod 56 toward the drums, 60 with the result that the slack is quickly

taken up. The simultaneous rotation of the drums 30 and 47 is produced as follows: As the staff 22 is being rotated in a clockwise direction, the drum 30 driven by the inter-meshing gears 24 and 34 will be rotated in the opposite direction, as indicated 70 in Fig. 5 and the clutch collar 36 being mounted to rotate with the staff 22 will rotate the sleeve 27 by its engagement with the teeth 39 of the enlargement 40, thus causing rotation of the sleeve 27 in unison with the staff 22 and effecting the winding of the chain 54 upon the drum 47, the latter being rotated in the direction indicated by the arrow in Fig. 5.

75 The inter-engaging teeth 38 and 39 are so designed that their inclination will offer sufficient resistance to prevent slippage therebetween during the time that the slack is being taken up by the chain being wound upon the drum 47, but this resistance will be overcome and the teeth 38 and 39 will slip or ratchet over each other when a greater and predetermined resistance is encountered, such as when the brake shoes are first 80 brought against the car wheels.

85 The simultaneous winding operation of the two drums 30 and 47 continues until the predetermined resistance has been encountered, whereupon the gripping action of the teeth 38 and 39 is overcome, thus allowing the sleeve 27 to remain stationary while the rotation of the staff is continued until the 90 brakes have been completely set. Retrograde movement of the sleeve and the staff is independently prevented by the separate locking pawls in engagement with the ratchet teeth 37 and 41 respectively. During this independent movement of the drum 30, the effective leverage ratio of the pull on the brake chain is obviously greatly increased due to the fact that the chain is being wound only on the drum 30 which is of 95 smaller diameter than the drum 47 and which is more slowly rotated than the drum 100 47, due to the reduction gears 24 and 34.

105 In releasing the brake mechanism, as the chain is unwound, the drums 30 and 47 will be simultaneously rotated in directions opposite to those indicated by the arrows in Fig. 5, and the clutch teeth 38 and 39, being in engagement, the sleeve 27 and the staff 22 will rotate in unison in a counter-clockwise direction until the lugs 51 on the sleeve 27 come into contact with the lugs 50 on the collar 49, whereupon the rotation of the sleeve 27 will be positively stopped, movement of the collar in a counter-clockwise direction being positively prevented by the formation of the teeth 52 thereon and fixed teeth 53. The rotation of sleeve 27 and the rotary drum 47 is thus positively limited, and as a result the amount of rotation of the drum 47 in taking up the slack 115 will be kept substantially constant. Under 120

normal conditions, when the drum 47 is thus brought to a stop, the chain will be completely unwound from the drum 30 and the latter will also come to rest, but additional 5 rotary movement of the drum 30 is permitted in case the chain is not completely unwound therefrom, by the teeth 38 slipping over the teeth 39 of the clutch.

In applying the brakes under normal conditions, the slack in the chain will be taken up during the time that the sleeve is rotated in a clockwise direction, from the position in which the lugs 51 are stopped against the lugs 50 on the collar, to a position where 10 the lugs 51 engage the opposite lugs 50, which involves slightly less than a half rotation, this amount of movement being sufficient in that the sleeves are simultaneously rotated during that time and the chain ends 15 simultaneously wound thereon to properly take up the normal amount of slack. As the brake shoe faces and the other parts of the brake rigging become worn, the slack in the chain will increase, thus requiring a 20 greater rotation of the sleeve 27 in taking up the slack. This is taken care of by the adjustable stop cap 49. Upon any slight additional rotation of the sleeve in a clockwise direction, due to a slight increase in the slack 25 of the brake chain over what is normally required, the lugs 51 on the sleeve being in engagement with the lugs 50 on the collar, will tend to move the latter in a clockwise direction, also, thus causing the teeth 52 30 on the collar to ratchet over the teeth 53 until the excessive slack has been taken up, whereupon the sleeve 27 having become stationary due to the release of the teeth 38 and 39 as hereinbefore described, the teeth 40 52 on the collar will re-engage with the teeth 53 with the collar in slightly advanced position. It will thus be seen that all the 45 excessive slack in the brake chain is automatically compensated for as it occurs and that the rotation of the sleeve 27, in taking up the slack, remains practically constant.

When it becomes necessary to replace the brake shoes, the ratchet collar is disengaged from the ratchet by engaging a proper tool 50 within the opposite openings 58 formed in the collar and manually raising the collar, whereupon, the drums 30 and 47 are free to rotate so that the chain may be entirely 55 unwound and the replacement of the shoes easily made. After the shoes have been replaced, rotation of the brake staff 22 in a clockwise direction will cause the chain to be rewound upon the drums 30 and 47. During 60 this operation, the sleeve 27 will be rotated relatively to the stop cap 49 until the lugs 51 engage the lugs 50, whereupon the stop cap will be rotated with the sleeve, the teeth 52 ratcheting over the teeth 53. This operation will continue until the slack of the 65 chain is completely taken up, whereupon

the teeth 38 and 39 on the collar 36 and the sleeve 27 respectively, will disengage, and rotation of the sleeve will be stopped, with the teeth of the stop cap reengaged with the fixed teeth 53 to prevent rotation of the 70 cap in a counter-clockwise direction.

I have herein shown and described what I now consider the preferred manner of carrying out the invention, but the same is merely illustrative and I contemplate all 75 changes and modifications that come within the scope of the claims appended hereto.

I claim:

1. In a hand brake; the combination with a rotatable chain winding drum; of means for rotating said drum; and means comprising a stop device movable with said drum until a predetermined resistance is reached, such stop device being adjustably secured in such position, and arranged to permit 80 limited reverse movement of said drum.

2. In a hand brake; the combination with a rotary brake drum; of means for rotating said drum in reverse directions to wind and unwind the brake chain; and means for 85 limiting rotation of said drum in one direction comprising, a pair of interengaging relatively adjustable clutch elements, one of said elements having a lost motion connection with said drum and the other clutch element being fixedly held against rotation, said clutch elements being normally operative to prevent rotation thereof in a counter-clockwise direction, but permitting relative rotation thereof in the opposite direction upon the lost motion being taken up by rotation of said rotating means in a 90 chain winding direction to compensate for increased slack in the brake chain, thereby 95 allowing relative automatic adjustment of 100 said clutch elements.

3. In a hand brake; the combination with a rotary brake drum; of means for rotating said drum in reverse directions, to wind and unwind the brake chain; and means for 105 limiting the rotation of said drum in one direction, said means including a movable element having a lost motion connection with said drum rotating means, and a fixed stop element, said first and second named 110 elements having co-acting means thereon permitting rotation of said first named element in a chain winding direction and positively preventing rotation of the latter in 115 an unwinding direction.

4. In a hand brake; the combination with a rotary brake drum; of means for rotating said drum; a toothed clutch collar rotatably journaled on said means, said collar and rotary means having inter-engaging lugs 120 thereon for limiting the relative rotation thereof; and a fixed stop element having clutch teeth thereon co-acting with the teeth of said collar to positively prevent rotation of said drum in one direction and permit- 125 130

ting rotation of said collar in the opposite direction.

5. In a hand brake; the combination with a vertical brake staff; of a chain winding drum rotatably journaled thereon; a sleeve formed integral with said drum and surrounding said staff; a pair of spaced lugs radially projecting from said sleeve; a ratchet wheel formed integral with said sleeve, said ratchet wheel having clutch teeth thereon; a ratchet wheel slidably mounted upon said staff for rotation in unison therewith, said ratchet wheel having clutch teeth co-acting with the clutch teeth of the first named ratchet wheel; a pair of locking pawls coacting with said ratchet wheels; a collar rotatably mounted upon said sleeve, said collar having clutch teeth thereon; a pair of spaced lugs on said collar co-acting with the lugs on said sleeve; a fixed member having clutch teeth co-acting with the teeth of said collar; a second rotary drum; and power transmitting gearing between said staff and said second named drum.
- 25 6. In a hand brake; the combination with a brake staff; of means for winding the chain, said means including a pair of drums of different diameters; means operatively connecting said drums to the brake staff; an adjustable stop; and a lost motion connection between said stop and one of said drums.

- 35 7. In a hand brake; the combination with a brake staff rotatable in reverse directions to wind and unwind the brake chain; chain winding means rotatably journaled upon said staff; locking means directly engageable with said chain winding means to prevent winding thereof; a second chain winding means positively driven by said staff; a releasable clutch connection between said staff and first named chain winding means automatically operable independent of said locking means; and means for limiting the

tation of said last named chain winding means in an unwinding direction.

8. In a hand brake; the combination with an operating element; of a tensioning member operatively associated with the brake rigging proper; means interposed between said operating element and tensioning member for multiplying the leverage ratio, said means automatically changing from a lower power leverage ratio to a higher power leverage ratio when a predetermined tension is reached; and automatically operable means for compensating for increases in slack to thereby maintain a substantially constant amount of slack in the brake mechanism.

9. In a hand brake; the combination with a brake staff; of winding drums mounted to rotate upon independent axes; a driving connection between said staff and one of said drums; a releasable clutch connection between the other of said drums and said staff, said clutch connection being adapted to be rendered ineffective to rotate said last named drum upon a predetermined resistance being encountered during the chain winding operation; and means for limiting the unwinding rotation of said last named drum, said means being movable to adjusted positions to compensate for increased slack in the brake chain.

10. In a hand brake, the combination with a rotatable chain winding drum; of means for rotating said drum to wind the chain thereon; means for limiting the unwinding rotation of said drum, said means being automatically advanced by the movement of said drum so as to compensate for increased slack in the brake chain.

In witness that I claim the foregoing I have hereunto subscribed my name this 25th day of October 1922.

JOHN F. O'CONNOR.
